UNITED STATES PATENT OFFICE.

WALKER GILL WYLIE, JR., OF RED BANK, NEW JERSEY.

AXMINSTER RUG.

Application filed April 3, 1926. Serial No. 99,485.

The present invention relates to Axminster rug making and the like and aims to provide certain improvements therein.

In the manufacture of Axminster rugs, carpets and the like, three distinct steps are involved, namely, setting, weaving and finishing. Of these steps, the setting and weaving are processes distinct from those employed in other forms of weaving.

10 Setting is the process which makes the design in the rug as well as the size and shape. It is the process that transposes the yarn from the reel spools to the loom spools. In the twenty-seven inch loom employed for 15 rug weaving, for example, there is a standard of 189 tufts or ends of yarn across the twenty-seven inch breadth which makes one row of tufts, hence the setting frame consists of a bank of 189 reel spools, the threads 20 from which are led forward through a comb or reed when winding or setting a loom spool.

In the weaving process the spools are carried by a chain movable over the loom, each 25 loom spool furnishing the yarn to make one row of tufts in the face or pile of the rug, where the loom spools are of the same width as the loom, the color of any particular tuft being previously determined from a master 30 design, in accordance with which the yarn is wound or set on the loom spools.

Heretofore, rectangular rugs only have been made on Axminster looms, and where 35 large rugs were desired, several strips formed on a narrow loom were seamed together. In recent years, however, a demand has sprung up for seamless rugs, and mills equipped with only narrow looms were forced to operate at either partial capacity 40 or to shut down completely.

According to the present invention I propose to use Axminster looms and especially these narrow looms for making rugs of any desired shape, either symmetrical or unsymmetrical, oval, circular, semi-circular, diamond-shaped or the like, and to accomplish this without wastage of yarn, which substance is the most costly item in rug manufacture. This I accomplish by winding or 45 setting the loom spools with yarn threads, the position and number of said threads corresponding to the arrangement and number of tufts in the corresponding tuft rows and then carry out the weaving process as at 50 present practiced.

A rug or the like as thus woven will have

a rectangular jute and cotton base as heretofore, but the tufted body will be limited to the outline desired and controlled by the number of threads or ends of yarn on the 60 various loom spools. If desired, the untufted portion is then trimmed away and the rug finished off in any desired manner. The invention also includes other features of novelty which will be hereinafter more fully 65 described.

By way of example I have shown an application of the invention to the making of an oval rug, and in the accompanying drawings illustrating the same:—

70 Figure 1 shows a rug as it comes from the loom.

Fig. 2 shows the rug in finished form.

Fig. 3 is a transverse section taken on the line 3—3 of Fig. 2.

75 Fig. 4 is a transverse section of a modified manner of finishing a rug.

Figs. 5 to 11 are elevations of the loom spools used to provide the rows of tufts corresponding to the lines 5—5 to 11—11 respectively in Fig. 1.

In practicing the present invention to make a non-rectangular or oval rug A, as shown in Fig. 2, the loom spools B are prepared by the setting process with yarn to the 85 proper numbers of threads or ends, colors and positions of the threads in accordance with a master design (not shown), it being understood that there will be a loom spool for each row of tufts in the rug. In Figs. 5 90 to 11 I have shown seven loom spools each with a plurality of threads of yarn wound thereon to correspond to the number of tufts for the rows in the rug A indicated by numbers similar to the figure numbers of said 95 spools. These, together with intermediate and the other spools, are mounted on the loom chain in proper sequence, and the weaving process is then carried out without modification.

100 In the weaving process, it will be understood that the warp chain and weft filling operate in exactly the same manner to provide the jute and cotton base of the rug as when weaving a rectangular rug having the 105 width of the loom, but it is to be observed that the tufts are only applied to the base in accordance with the outline of the tufted portion of the rug desired. There is, therefore, no wastage of yarn at the four corners 110 of the rug base which are cut away in the finishing operation.

A rug woven according to the present invention may be finished off in any manner desired, and I have herein shown two ways in which this may be accomplished. According to the one method, the untufted base C may be trimmed around the dotted lines D substantially parallel to the base of the tufted portion, then bent back upon themselves along the base of the tufted body and secured by a line of stitching E, as best shown in Fig. 3. Another method is to trim away the entire untufted base and sew a tape around the edges of the rug, as best shown at F in Fig. 4.

In winding or setting the yarn on the loom spools from the reel spools on the setting frame, the threads are first passed through the teeth of a comb or reed, the position of each tooth determining the position of a particular tuft in a row in the finished rug. In a twenty-seventh inch loom, for example, there are 189 tufts to a row, hence there are 190 teeth to the guiding comb or reed. And where the entire loom spool is to be wound or set, the enlarged ends of the spool serve as collars to prevent spreading of the terminal threads of yarn, as best shown in Fig. 11 of the drawings. But where the terminal thread or threads are to be spaced from the respective ends of the spool as shown in Figs. 5 to 10, means for preventing such spreading may be employed. In my copending application Serial No. 105,081, filed April 28, 1926, I have shown and described a preferred manner of accomplishing this end.

From the foregoing description it will be appreciated that by the present invention narrow Axminster looms can now be put to useful and profitable production, and further, that rugs and the like of any arbitrary shape and design can be produced without wastage of yarn.

While I have shown and described a preferred method of practicing my invention, it is to be understood that the specific details herein set forth are merely illustrative of the workings of the invention, and that modifications of said details may be resorted to without departing from the spirit of the invention.

What I claim is:

1. The method of making a pile fabric or the like having a tufted body and a woven base, the area of the tufted body being less than that of the woven base upon which it is formed, upon an Axminster type loom, which comprises weaving a rectangular base and simultaneously forming said tufted body thereon in the form of tuft rows of desired width, by using loom spools having the tufting threads wound thereon, the

position and number of said threads corresponding to the arrangement and number of tufts in the corresponding tuft rows.

65

2. The method of making a rug or the like having a tufted body of varying width on an Axminster type loom, which comprises weaving a rectangular rug base and simultaneously forming said tufted body thereon in the form of tuft rows of different widths by using loom spools having the same number of ends of yarn as there are tufts in their corresponding tuft rows.

70

3. The method of making a rug or the like having a tufted body of varying width on an Axminster type loom, which comprises weaving a rectangular rug base and simultaneously forming said tufted body thereon by using loom spools, one terminal yarn thread of which is spaced from its respective end of the spool, said spacing being different on different spools.

75

4. The method of making a rug or the like having a tufted body of non-rectangular form on an Axminster type loom, which comprises weaving a rectangular base and simultaneously forming said tufted body thereon by using loom spools, the terminal yarn threads of which are spaced from their respective spool ends, but to varying distances from said ends on different spools, the yarn windings on said spools being such as to provide a tufted body of varying width which is symmetrical with respect to a median line of said tufted body.

80

5. The method of making a rug or the like of varying width on an Axminster loom, which comprises weaving the rug base of greater area than the tufted rug body, trimming away the excess of the untufted rug base and finishing off the raw edges of the base.

85

6. The method of making a rug or the like of varying width on an Axminster loom, which comprises weaving the rug base of greater area than the tufted rug body, trimming away the excess of the untufted rug base along lines substantially parallel to the tufted body but spaced therefrom, and finishing off the raw edges of the base by bending them back upon themselves along the edges of the tufted body and securing said bent back portions in place.

90

7. An intermediate product in the making of an Axminster rug which comprises a woven rectangular base having a tufted body portion thereon of varying width, the tufted body portion being adapted to constitute the face of the rug.

95

In witness whereof, I have hereunto signed my name.
